Patented Nov. 19, 1918.

FIG. 1

FIG. 2

FIG. 3

Diagram illustrating a curved pipe section with various dimensions labeled on its segments. The segments are labeled with the following values: 5, 8, 22, 3, 8, 22, 3, 8, 5. The pipe is shown in a U-shaped bend, with the segments labeled 5, 8, and 22 appearing on the left side, and the segments labeled 3, 8, 22, 3, 8, and 5 appearing on the right side.

UNITED STATES PATENT OFFICE.

ALBERT McALLISTER, OF PITTSBURGH, PENNSYLVANIA, ASSIGNOR TO ASBESTOS PROTECTED METAL COMPANY, OF PITTSBURGH, PENNSYLVANIA, A CORPORATION OF PENNSYLVANIA.

VENTILATOR.

1,285,275.

Specification of Letters Patent.

Patented Nov. 19, 1918.

Application filed July 18, 1917. Serial No. 181,259.

To all whom it may concern:

Be it known that I, ALBERT McALLISTER, a citizen of the United States, and resident of Pittsburgh, in the county of Allegheny and State of Pennsylvania, have invented certain new and useful Improvements in Ventilators, of which the following is a specification.

My invention relates to the construction 10 of ventilators used to connect the interior with the exterior of buildings, vessels, chimneys, and similar structures, to ventilate such structures.

One object of this invention is the provision of a ventilator of improved construction having novel means wherein the free outflow of air or other gaseous fluid through the ventilator is obtained and maintained and whereby such outflow is augmented by 20 the action of air currents striking the ventilator, and the entrance and passage of rain and snow into and through the ventilator is avoided and prevented.

Another object of the invention is the provision of a ventilator having the novel constructions, combinations, and arrangements of parts shown in the drawings, to be fully described hereinafter and to be particularly pointed out in the appended claims.

Referring now to the drawings, forming part of this specification, Figure 1 is a sectional elevation of a ventilator embodying my invention.

Fig. 2 is a sectional plan, the section being 25 taken on the line II—II of Fig. 1.

Fig. 3 is an elevation of the ventilator shown in Figs. 1 and 2.

Fig. 4 is a plan of the ventilator shown in Figs. 1, 2, and 3.

Fig. 5 is a transverse section on the line V—V of Fig. 1 showing details in the construction of the ventilator of Figs. 1, 2, 3, and 4.

Fig. 6 is a transverse section similar to 45 that of Fig. 5, showing a modification in the construction of the ventilator.

In the accompanying drawings, the numeral 2 designates an eduction pipe, cylindrical in cross section as shown, which is 50 adapted for attachment by its lower end to a building, vessel, chimney or the like, to exhaust air, smoke, or similar gaseous fluid therefrom, and secured on the outer surface of the eduction pipe is a plurality 55 of flat sheets or plates forming a series of

equally spaced, radial vanes or wind guides 3, these vanes extending lengthwise vertically for some distance above the upper end 4 of the eduction pipe. Surrounding the upper end of the pipe 2 is a frusto-conical 60 hood 5, this hood being conveniently supported by the upwardly and inwardly tapering outer edges 6 of the vanes 3 and the vanes, preferably, project somewhat below and taper inwardly and downwardly from 65 the lower edge 7 of the hood, as shown. The side surfaces of the vanes 3, the outer surface of the pipe 2, and the opposite inner surface of the frusto-conical hood 5 form a series of upwardly tapering vertical air 70 channels 8.

The small or uppermost end 9 of the hood 5 is of substantially the same diameter as the central eduction pipe 2, and, as is clearly shown in Fig. 1, this upper end of the hood 75 is considerably above the upper end 4 of the eduction pipe, so that the series of channels 8 open transversely or inwardly immediately above the end 4 of the eduction pipe 2 into the chamber 20.

Fastened on the outer surface of the frusto-conical hood 5 is a plurality of equally spaced, lengthwise vertical plates forming a series of radial vanes or wings 10 which have substantially vertical outer edges 11. The 85 outer edge 11 of each of the wings 10 has an offset or jog 12 at the upper end thereof, and supported on these jogs is a tubular shield 13. The shield 13, which is of a diameter the same or, as shown, slightly less than that 90 of the lower or large end 7 of the frusto-conical hood 5, extends from slightly below to some distance above the upper edge 9 of the hood 5 and its overlapping lower end 15 co-acts with the wings 10 and upper end of 95 the hood 5 to form a series of vertical passages or channels 16.

Secured within the shield 13 in the upper end thereof, is a conical top or cap 17, this cap being fastened to the shield by straps 18, 100 and being smaller in diameter than the internal diameter of the shield so as to provide an annular passage 19 within the shield connecting the chamber or space 20 below with the exterior of the shield above the 105 cap 17.

Preferably the vanes or guides 3 and the wings 10 will be separately formed, as shown in Figs. 1, 2, and 5, with flanges 21 on the edges thereof for attachment to the frusto- 110

conical hood 5, the vanes 3 also having flanges 22 on the inner edge thereof to fasten them to the tubular eduction pipe 2 (see Fig. 5). In such case the hood 5 will be integrally formed as shown in Figs. 1, 2, and 5. Obviously, however, the vanes and wings may be combined or formed integrally and the hood made in segments 5 with the side edges thereof flanged for attachment to the vanes in the manner shown in Fig. 6. In either case the parts may be fastened together by rivets as shown, or by electric spot welding, brazing, soldering, or other known manner.

15 The central tubular pipe 2 forms an eduction pipe through which the air or other gaseous fluid passes from the building or other structure to be ventilated into the atmosphere. The wind upon striking the outer 20 surface of the eduction pipe and the surfaces of the vanes or wind guides 3 is deflected and caused to travel upwardly within the passages 8 and pass radially inward into the chamber 20 above the upper end of the 25 eduction pipe 2 at one side thereof and out of the ventilator in a downward direction through the passages 8 on the opposite side. At the same time the surfaces of the wings 10 and outer surface of the frusto-conical 30 hood changes the direction of travel of the wind and causes it to pass upwardly through the passages 16 into the chamber 20 to supply an added amount of air. The currents of air in passing through tapering passages 35 8 into the chamber 20 create and maintain a partial vacuum therein, and by an aspirator action cause suction within the eduction pipe 2 which increases the flow of air or gases through the eduction pipe and adds greatly 40 to the efficiency of the ventilator.

When the air is stationary on the outside of the ventilator the large annular opening 19 within the shield 13 provides for the easy 45 exit of air or gases through the ventilator while the conical top or cap 17 and conical hood will at all times prevent the entrance of snow and rain into the eduction pipe 2.

The advantages of my invention, which will be readily appreciated by those skilled 50 in the art, arise from the novel arrangement of vanes and superposed sets of air passages on the upper end of the eduction pipe of the ventilator.

Modifications in the construction and arrangement of the parts forming my improved ventilator may be made without departing from my invention as defined in the appended claims.

I claim:

60 1. A ventilator comprising an eduction pipe, a conical hood surrounding said eduction pipe and extended above and below the upper end thereof outside of said pipe and separated therefrom to form therewith 65 an external passage tapering upwardly with

its wider inlet located below the top of said pipe, a cap member located above said hood in proximity thereto, to be struck by a current of air passing up between the said hood and eduction pipe at one side and to 70 deflect the said air downwardly at the opposite side of said hood, vanes extended outwardly from the said hood to form side walls of a series of air channels on the outside of said hood which coöperates with the 75 said cap member to cause air currents passing through said channels to also strike against the underside of said cap member, and a shield member coöperating with said cap member and with said vanes and ex- 80 tended below the cap member and the upper portion of the said hood to form an outer wall for the upper portion of said channels.

2. A ventilator comprising an eduction 85 pipe, upwardly tapering wings radiating from the outside of said pipe and extended above the latter and provided with inclined outer edges, a conical hood supported by said inclined outer edges and extended above 90 and below the top of said pipe to form therewith a series of tapering air passages having substantially large inlets located below the top of said pipe and between the latter and the base of said hood for entrance 95 therein of a current of air moving directly upward alongside and in contact with said pipe, and narrower outlets located above said pipe, vanes radiating from the outside of said hood and having inclined inner edges 100 to engage said hood and extended below the top of said eduction pipe to form on the outside of said hood downwardly tapering side walls for a series of air channels which are external to said hood and extended below the upper end of said eduction pipe 105 and a cap member located above said hood in proximity thereto and coöperating with both sets of vanes to be struck by currents of air passing upwardly on the inner and 110 outer surfaces of said hood.

3. A ventilator comprising an eduction pipe, a conical hood surrounding said eduction pipe and extended above and below the upper end thereof outside of said pipe and 115 separated therefrom to form therewith an external passage tapering upwardly with its wider inlet located below the top of the said pipe to receive a current of air passing directly upward on the outside of said pipe, vanes extended outwardly from said hood to form side walls of a series of air channels on the outside of said hood, a shield member surrounding the upper part of said 120 vanes and forming with said hood opposing walls of said channels, and a cap member located above said hood in proximity thereto and provided with an air passage which coöperates with the eduction pipe to form 125 an outlet for gases issuing therefrom and 130

with said external channels to form an inlet thereto for downwardly moving currents of air.

4. A ventilator comprising an eduction pipe, a conical hood surrounding said eduction pipe and extended above and below the upper end thereof outside of said pipe and separated therefrom to form therewith an external passage tapering upwardly with its wider inlet located below the top of said pipe, a shield member located outside of the upper portion of said conical hood and sep-

arated therefrom, wings interposed between said hood and pipe to form air passages, vanes interposed between said hood and 15 shield to form air channels, and an upwardly conical cap in proximity to the upper end of said conical hood and coöperating with the air passages within the hood and the air channels on the outside of said 20 hood for the purpose specified.

In testimony whereof I have hereunto set my hand.

ALBERT McALLISTER.
